UNITED STATES PATENT OFFICE.

GEORGE F. DE WEIN, OF MILWAUKEE, WISCONSIN, ASSIGNOR TO ALLIS-CHALMERS COMPANY,
OF MILWAUKEE, WISCONSIN, A CORPORATION OF NEW JERSEY.

ROASTING-FURNACE.

No. 899,591.

Specification of Letters Patent. Patented Sept. 29, 1908.

Application filed January 4, 1907. Serial No. 350,754.

To all whom it may concern:

Be it known that I, GEORGE F. DE WEIN, a citizen of the United States, residing at Milwaukee, in the county of Milwaukee and 5 State of Wisconsin, have invented a certain new and useful Roasting-Furnace, of which the following is a specification.

This invention relates to a roasting furnace, and more particularly to the cooling 10 device applied to the rotary stirring shaft.

The object of the invention is to provide a discharge means for the cooling medium circulating in the rotary stirring shaft, so constructed as to prevent flooding of the liquid 15 cooling medium during its forcible discharge from the stirring shaft caused by the formation of gas or vapor by the volatilization of the liquid cooling medium.

In the drawings,—Figure 1 is a vertical 20 central section through the stirring shaft, the furnace being shown in outline. Fig. 2 is an enlarged horizontal section on the line II—II of Fig. 1. Fig. 3 is an enlarged horizontal section on the line III—III of Fig. 1.

The invention has been illustrated in the 25 drawings in connection with a McDouall type of furnace, that is, one with superposed hearths. It is applicable to any form of furnace where a rotary stirring shaft is used, or 30 in connection with any other form of cooled stirring arms. It is not necessarily limited to a stirring means for a roasting furnace, but may be applied to any cooled stirring means, the only essential being that the shaft 35 is designed for using a liquid cooled medium.

The furnace 1 is illustrated as having circular side walls and hearths 2, 2, and a top arch 3. The rotary stirring shaft 4 is shown as centrally mounted and has a means 41 at 40 the bottom for providing a step bearing. Any means, not shown, may be used for rotating the shaft. The shaft 4 has arms 42 extending horizontally and radially therefrom, and as shown in the drawing, they extend 45 in two planes at right angles to each other. The shaft 4 and arms 42 are hollow and are in communication with each other. The shaft 4 is preferably constructed in sections, and, as shown in the drawing, each 50 section has preferably attached thereto four arms.

The cooling means for the rotating shaft consists of a stationary inlet pipe 5 extending down through the shaft 4 and terminating 55 near the bottom of the shaft. A stuffing box

43 at the upper end of the shaft 4 serves to prevent escape of cooling medium around the pipe 5 and also allows for rotation of the pipe 4 about the stationary pipe 5.

The outlet means for the cooling medium 60 consists of three separate outlet pipes 6, see Fig. 3, for the liquid medium, and three other separate outlet pipes 7, see Fig. 2, for the gas or vapor. These pipes 6 are short elbow pipes discharging downwardly into 65 the annular trough 64, having an outlet 65 for the final discharge of the liquid cooling means. The annular trough 64 is supported upon the furnace in any convenient manner. The discharge pipes 6 lead from an enlargement 70 46 above a reduced portion at the upper end of the shaft 4 and immediately below a screen 47 in the enlargement 46 and surrounding the inlet pipe 5. The discharge pipes 7 lead from the enlargement 46 of the 75 shaft 4 and extend upwardly at an angle of about 45 degrees to the vertical for a short distance and then continue upwardly in a vertical direction. The discharge pipes 6 lead first in a horizontal direction and then 80 downwardly in a vertical direction. The gas or vapor discharge pipes 7 alternate in plan view with the liquid discharge pipes 6.

The operation of the device is as follows: A liquid cooling medium, preferably water, 85 is introduced into the stationary supply pipe 51 connecting with the top of the stationary inlet pipe 5. The cooling liquid after being discharged into the lower end of the stirring shaft 4 will circulate from that point through 90 the shaft and arms and its discharge will take place from the upper end of the shaft through the outlet means therefor. During this circulation any gas or vapor or steam into which portions of the cooling medium may 95 have been transformed due to heat taken up from the furnace, will be carried along up with the liquid cooling medium to the outlet means. Upon reaching the enlargement 46 of the shaft 4, the liquid and gaseous mixture 100 will strike the screen 47, the gas being carried through the screen while the liquid will practically all be stopped in its upward course. The liquid will then pass out through the discharge pipes 6, while the gas 105 or vapor will be discharged through the outlet pipes 7. The liquid will be discharged into the trough 64 and finally through the outlet 110 65, from whence it will be conducted away in any desired manner. This inven-

tion therefore provides a discharge means for the cooling medium of a stirring shaft which will prevent the spouting of the liquid from the shaft in a violent manner because of the gas or steam formation which is liable to take place. Such possible violent discharge from the cooling means heretofore employed is a source of great annoyance due to overflow from the trough 64 caused thereby. In the present invention the steam and water is effectively separated prior to discharge, the gas or steam passing through separate outlet pipes, while the water passes through separate discharge pipes. The greater height of the upper discharge pipes measured from the beginning of liquid discharge, provides a sufficient head to prevent the discharge of any liquid which may splash through the screen 47. It should be noticed that the discharge of the gas, vapor or steam is such that its direction is not greatly changed. It is almost in line with the shaft 4, there being but two angles of 135 degrees each in the course of its discharge. Moreover, the separate discharge of the liquid from that of the gas will insure a more complete separation so that the chances are lessened for discharge of liquid through the gas or steam outlets.

It should be understood that it is not de-

sired to be limited to the exact details of construction shown and described, for obvious modifications will occur to a person skilled in the art.

What is claimed and desired to secure by Letters Patent, is:

1. The combination of a hollow stirrer, inlet means thereto for a liquid cooling medium, outlet means therefrom for liquid discharge and separate outlet means for gas discharge communicating with the stirrer at a higher level than the communication therewith of the liquid outlet means.

2. The combination of a hollow stirrer, inlet means thereto for a liquid cooling medium, downwardly extending discharge means for the liquid and separate upper upwardly discharging means for gas.

3. The combination of a hollow stirrer, inlet means thereto for a liquid cooling medium, outlet means therefrom for liquid discharge, separate outlet means for gas discharge, and a screen in the stirrer between the liquid and gas outlets.

In testimony whereof, I affix my signature in the presence of two witnesses.

G. F. DE WEIN.
